ADJUSTABLE LOG TRIPPING SAWMILL
DECK BLOCK

Hugh W. Clark, Troy, N. C.

Application December 23, 1949, Serial No. 134,831

2 Claims. (Cl. 143—96)

1

My invention relates to a new and useful improvement in an adjustable log tripping sawmill deck block adapted for use in releasing logs for passage onto the carriage which will convey the logs to the saw which will operate upon the logs. Usually the logs are placed upon a platform or skid which is inclined downwardly to a carriage onto which the logs are permitted to pass individually after which the log which has passed upon the carriage is secured in position and the carriage then moved to convey the log past the rotating saw. The present invention is intended as a means for releasing the logs individually for passage onto the carriage while at the same time restraining the succeeding logs from movement onto the carriage.

It is an object of the present invention to provide a log tripping sawmill deck block so arranged and constructed that it may be easily and quickly operated and eliminate the necessity of stationary blocks for preventing the logs from movement onto the carriage.

Another object of the invention is the provision of a log tripping sawmill deck block so arranged and constructed that it will be slightly automatic in its operation moving to deliver a thrust to the log passing onto the carriage and moving to abutting position against subsequent logs in response to spring pressure.

Another object of the invention is the provision of a log tripping sawmill deck block which may be easily and quickly mounted in position on the skid or support.

Another object of the invention is the provision of a log tripping sawmill deck block so arranged and constructed that it will be adjusted within certain limits for regulating the distance of movement for the log toward the carriage before the log is abutted and restrained.

Another object of the invention is the provision of a log tripping sawmill deck block so arranged and constructed that it may be swung to lie at right angles to the normal position to permit a wider cut on the log.

Other objects will appear hereinafter.

It is recognized that various modifications and changes may be made in the detail of structure illustrated without departing from the invention itself and the present illustration is intended to be but one embodiment of the invention.

Forming a part of this specification are drawings in which:

Fig. 1 is a side elevational view of the invention applied to a skid illustrating a section taken through the carriage.

Fig. 2 is a top plan view of an installation of the invention.

Fig. 3 is a side elevational view of the invention showing it applied slightly enlarged over Fig. 1.

Fig. 4 is a top plan view of Fig. 3.

Fig. 5 is a view the same as Fig. 4 with the butting member swung outwardly at right angles.

Fig. 6 is a front elevational view of the invention showing it applied.

Fig. 7 (Sheet 1) is a sectional view taken on line 7—7 of Fig. 5.

Fig. 8 is a fragmentary sectional view taken on line 8—8 of Fig. 5.

15 In sawing boards or other similar material, it is customary to use a movable carriage. Beams 16 and 17 support tracks 18 on which roll the traction wheels 19 supported by the axle 20 which is carried by the beams 21 of the carriage. These beams 21 are connected by cross members 22 which serve to support the upwardly projecting standards 23 which carry the log gripping member. This construction is well known and in common use and of itself forms no part of the present invention.

20 A skid or platform is supported by the standards or uprights 24 which are connected to each other by the beam 25 so that a support is thus provided for the skid bars or beams 26 which are at an incline to the carriage and down which the logs 27 have a tendency to roll onto the carriage. It is of course necessary that these logs be permitted to pass individually onto the carriage so that a single log is secured in position for the sawing operation while the successive logs are held in position on the skid.

25 The invention comprises an angle iron 28 (Fig. 6) which is fastened on the members 26, the members 26 being preferably recessed, so that the upper face of the angle iron 28 will lie flush with the upper face of the member 26. Carried on the vertically extended part of the angle iron 28 at opposite ends thereof are the housings 29 and 30 open at their opposite ends so that there is thus provided a channel 31 in which the guide plate 32 may slidably engage. Secured to the guide plate intermediate its ends and projecting outwardly therefrom is a pair of spaced apart lugs 33. Positioned between these lugs 33 and 40 pivoted thereto by the pin 33a is a hub 34. Secured to the hub 34 and projecting outwardly therefrom are the spaced apart arms 35 and 36 so that the hub 34 together with these arms forms a yoke.

45 Engaging between these arms 35 and 36, at an

apex, is a triangle cam plate 40 which is pivoted to the arms 35 and 36 by means of the pin 37. Fixedly mounted on the arm 35 is a collar 38 which forms a hub and through which the pin 37 projects and a cotter pin 39 is projected through this collar 38 and through the pin 37. The plate 40 is provided with a central reinforcing and abutment rib 41 which extends outwardly from the pivoted end to the arcuate plate 42. Embracing the pin 37 is a coil spring 43, one end 44 of which bears against a bracket arm 45 mounted on the arm 35. The other end 46 of the coil spring 43 engages the reinforcing rib 41 so that the plate 40 is normally retained in its upwardly rocked position shown in Fig. 1 or Fig. 3. When in this position the edge 57 of the plate 40 would engage a log resting on the skid bars 26 and prevent the passage of this log downwardly onto the carriage. When it is desired to release a log for passage onto the carriage the plate 40 may be rocked downwardly, manually or in any other desired manner, against the tension of the spring 43 so that the face 57 of the plate 40 would lie flush with the upper face of the skid bars 26. If the log passing downwardly would ride clear of the face 57 the spring would cause the plate 40 to rock upwardly so that the arcuate face 42 would thus engage the periphery of the log and deliver a thrust to the log to facilitate the passage onto the carriage.

Swingably mounted on the end of the arm 35 is a plate 47. Secured to the plate 47 and projecting outwardly therefrom, at right angles to the face thereof, is a guide rod 48 on which is positioned, in embracing relation, a coil spring 49. One end of this coil spring 49 bears against the face of the plate 47 and the opposite end seats in a cup 50 which is mounted on the arm 51, which is secured in fixed relation to the slidable plate 32. At times it is desired to enlarge the cut 63 which is made on the log 27. Particularly is this so if it is desired to split the log. When such is the case the plate 40 may be swung on the pivot 33a from the position shown in Fig. 4 or Fig. 1 to the position shown in Fig. 5 so that the plate 40 is thus extended outwardly at right angles to the face of the skid bars 26 so as to afford the desired clearance for the log as it is carried along by the carriage. The construction is such that the spring 49 normally resists this outward swinging of the plate 40 and such that when swung to fully outward position the plate 47 will be rocked into the position shown in Fig. 5 so as to carry the end of the rod which is secured to the plate 47 slightly past center. In this way the spring 49 tends to resist swinging of the plate 40 from the position shown in Fig. 5.

Secured to and projecting outwardly from the rear end of the angle iron 28 is a hook 52 to which is attached one end of the spring 53, the other end being attached to hook 54 projecting downwardly from the lug 33 which is secured to the plate 32 so that the spring 53 serves to normally resist forward sliding of the plate 32, that is a sliding to the left of Fig. 1 or Fig. 3. Projecting downwardly from this plate 32 is a bracket 58 as clearly shown in Fig. 3. Pivoted at one end to the bracket 58 is an arm 59 carrying a stud 60 adapted to engage in the recess 62 formed in the plate 61 which is fixedly mounted on the skid bars 26. The construction is such that the plate 32 may be slid forwardly to various positions, against the tension of the spring 53 and secured in these positions through engagement of the stud 60 in one of the notches 62. This permits an adjust-

ment of the cam plate 40 relatively to the carriage so that the logs 27 on the skid bars may be checked at various positions. This is desirable depending upon the size of the logs and also on the depth of cut to be made.

Secured to the arm 35 and projecting upwardly therefrom is a rod 55 having the angularly turned end 55 which projects inwardly under the flange 42 toward the plate 40 and which is adapted to engage the flange 42a to resist upward rocking movement of the plate 40. In Fig. 3 I have illustrated by the dotted line a step in the forward adjustment of the mechanism. Since the plate 40 is carried by the plate 32 it is obvious that a sliding movement of the plate will effect a sliding movement of the cam plate 40.

This cam plate in addition to serving as an abutment also serves as a thrust delivering member as previously mentioned.

With a log tripping cam constructed in this manner, a speed in operation becomes possible and a most efficient checking or tripping device is thus afforded.

What I claim is:

1. A log tripping sawmill deck block of the class described, comprising: a supporting member adapted for mounting on a stationary surface; a plate slidably mounted on said supporting member; a rockable cam carried by said plate and having an end face formed arcuate; a spring for normally retaining said cam rocked upwardly to project above the upper face of said supporting member; a stationary abutment member for limiting rocking movement of said cam in either direction; a spring for normally retaining said plate slid to a predetermined position relatively to said supporting member and resisting movement of said plate from said position; an arm carried by said plate; an engagement member carried by said arm; and a stationary bracket having a plurality of notches formed therein for reception of said engagement member for securing said plate when slid to various positions from its normal position.

2. A log tripping sawmill deck block of the class described, comprising: a supporting member adapted for mounting on a stationary support; a plate mounted on said supporting member; a pair of lugs extending outwardly from said plate; a yoke pivotally mounted between said lugs, the arms of said yoke being adapted to extend parallel to said plate or at right angles thereto; a spring actuated toggle for normally retaining said yoke in either of said positions; a triangular cam plate pivotally mounted at an apex between the arms of said yoke and rockable upwardly and downwardly; and a spring for normally retaining said plate rocked upwardly to project above the surface of said supporting member and resisting downward rocking of said plate.

HUGH W. CLARK.
